UNITED STATES PATENT OFFICE.

CHARLEY A. KULLBERG, OF HAWICK, MINNESOTA.

MOTOR-DRIVEN HARVESTER.

SPECIFICATION forming part of Letters Patent No. 576,588, dated February 9, 1897.

Application filed February 1, 1896. Serial No. 577,659. (No model.)

To all whom it may concern:

Be it known that I, CHARLEY A. KULLBERG, a citizen of the United States, residing at Hawick, in the county of Kandiyohi and State of Minnesota, have invented certain new and useful Improvements in Motor-Driven Harvesters; and I do hereby declare the following to be a full, clear, and exact description of the invention, such as will enable others skilled in the art to which it appertains to make and use the same.

My invention relates to harvesters, and has for its object to improve the construction of the same with a view of giving increased efficiency and making practicable a machine of very large capacity.

To these ends my invention comprises the novel devices and combinations of devices hereinafter described, and defined in the claims.

It is thought that it will assist the reader in distinguishing the broad or generic features of my invention from the more specific details of construction to note in advance the following facts:

In adapting the machine for heavy work I provide a motor which I preferably mount on the machine-frame, and provide variable drives extending from the motor to the traction-wheels of the machine and to the harvesting mechanism. These drives are arranged to operate the respective devices driven thereby, either simultaneously or independently, under the action of the motor.

The motor which I prefer to employ is an ordinary gas or gasoline engine. In connection with this gas or gasoline engine and the drive or drives extending therefrom I provide a reversing device, by means of which the direction of rotation of the traction-wheels of the machine may be reversed to back up the machine. I also provide raising and lowering connections, which are applied to the opposite ends of the harvester-platform and which are adapted to be operated to raise the ends of said platform, either simultaneously or independently, at will.

So far as the broad principle of my variable drive or driving mechanism above referred to is concerned it is not necessary that the same be used in connection with a motor which is carried by the machine and serves to pro-

pel the same, but it may be employed in any manner whereby the speed of the harvesting mechanism may be varied with respect to the advancing movement of the machine.

It may be here remarked that the expression "harvesting mechanism," as used throughout this specification and the claims, is used in a sense broad enough and is intended to include any one or more of the devices used in the act of harvesting, namely, the binder, the cutting device, the canvases or carriers, and the reel.

My invention also comprises certain minor details of construction, which will be herein-after described, and defined in the claims.

The preferred form of my invention is illustrated in the accompanying drawings, therein like letters referring to like parts throughout the several views.

Figure 1 is a plan view of the machine, some parts being removed. Fig. 2 is a side elevation looking from the right-hand side of the same, some parts being also removed. Fig. 3 is a diagram view showing certain parts of the machine, looking from the left-hand side of the machine. Fig. 4 is a detail showing a movable fulcrum-block and support for one of the raising and lowering levers, some parts being broken away. Fig. 5 is a transverse vertical section taken on the line $x^5 x^5$ of Fig. 4, looking toward the rear. Fig. 6 is a horizontal section taken through a portion of the left end of the machine on the line $x^6 x^6$ of Fig. 3. Fig. 7 is a detail view in perspective, showing parts of one of the variable-speed driving mechanisms constituting my invention. Fig. 8 is a horizontal section also showing parts of said variable-speed driving mechanisms. Fig. 9 is a detail in side elevation, showing the latch devices for controlling the raising and lowering connections of the harvester, some parts being broken away. Fig. 10 is a transverse section taken substantially on the line $x^{10} x^{10}$ of Fig. 9; and Fig. 11 is a detail view, in right side elevation, showing the pivotal connection between the right member of the raising and lowering levers and the platform-segment.

Referring especially to Figs. 1 and 2, a indicates the platform-frame, a' the endless platform carrier or canvas, a^2 the sickle, and a^3 the sickle-pitman driven from crank-disk a^4 on the crank-shaft a^5 , all of the ordinary

harvester construction. In a like manner to the ordinary harvester the right end of the platform a is provided with a pair of rigidly-secured loop-segments a^6 , having on their interior rear edge rack-teeth a^7 . With these rack-teeth a^7 engage a pair of pinions a^8 , both of which are rigidly secured on a short shaft a^9 . It is on this short shaft a^9 that the bull-wheel of the ordinary harvester is mounted; but, as will later appear, I pivotally secure the forward end of the right member of the lifting-levers used in my present invention to this shaft a^9 .

In my present invention, for the purpose of carrying and operating the harvester proper, I employ a large traction-truck, upon which is mounted a gas-engine or other suitable motor, provided with driving connections for operating both the traction-wheels of the truck and the cutting and binding mechanism of the harvester.

As shown, the traction-truck comprises a large skeleton-like frame b , in the forward portion of which is loosely mounted a pair of laterally-spaced traction-wheels b' , and in the rear portion of which frame is pivotally mounted a rudder-wheel b^2 . Rudder-wheel b^2 is directly mounted in a swiveled bracket b^3 , the stem portion of which projects upward through a suitable seat in the rear end of said truck-frame b and is provided with a sheave b^4 .

The rudder-wheel b^2 is moved, in the act of steering the traction-truck, by means of a vertical shaft b^5 , mounted in a bracket b^6 on the truck-frame b , provided at its upper end with a hand-wheel b^7 and at its lower end with a small sheave b^8 and, by an endless cable b^9 , wrapped around said sheaves b^4 and b^8 .

As shown in the accompanying drawings, the harvester-platform a is supported from the traction-truck b , with freedom for both vertical and pivotal adjustment with respect thereto, by means of a pair of longitudinally-disposed levers c and d . Of these levers the lever c , which is the longer of the two, has its forward end pivoted on the pinion-shaft a^9 and is fulcrumed at its intermediate portion on a pin c' , carried by an adjustable fulcrum-block c^2 , mounted for vertical adjustment in a bracket c^3 , rigidly secured to the forward right-hand corner of the truck-frame b .

It will be noted that the bracket c^3 is provided with vertical slots c^4 in its sides, through which the projecting ends of the fulcrum-pin c' work, to hold the block in position. The vertical adjustment of this fulcrum-block c^2 is effected by means of a screw-rod c^5 , having screw-threaded engagement through the upper head of the bracket c^3 , attached at its lower end by means of a swiveled connection c^6 to the said block c^2 , and provided at its upper end with a hand-wheel c^7 .

The pinion-shaft a^9 may be locked to the forward end of the lever c and thereby held in any adjusted position with respect to the segments a^6 and a^7 by means of a worm-gear c^8 , rigid on the shaft a^9 , and engaged by a

worm c^9 on the end of a rod c^{10} , which rod is mounted for rotary but fixed against endwise movement in bearings c^{11} , secured to said lever c .

The lever d is much shorter than the lever c and is fulcrumed at its intermediate portion in a manner substantially identical with that just described in connection with said lever c . In this case d' indicates the fulcrum-pin passing through said lever d and an adjustable fulcrum-block d^2 , with its projecting ends working in vertical slots d^4 , formed in the sides of the bracket d^1 , which bracket in this case is rigidly secured to the forward left-hand corner of the truck-frame b .

d^5 is a screw-rod working through the bracket d^1 and swiveled to the fulcrum-block d^2 .

The forward end of the lever d is pivoted on a projecting pin d^6 , carried by a vertically-movable plate d^7 , loosely mounted in the flanged bracket d^8 , secured to the left end of the platform-frame a . The rear flange of the bracket d^8 is provided with rack-teeth d^9 , with which engages a pinion d^{10} , formed integral with a worm-gear d^{11} , both of which are loosely mounted on the stud or pin d^6 , between the lever d and the plate d^7 .

d^{12} is a worm carried at the end of a rod d^{13} and engaging the worm-gear d^{11} . The rod d^{13} is mounted for rotary but fixed against endwise movement in bearings d^{14} , carried by the lever d . By this means, as is obvious, the left end of the platform may be vertically adjusted with respect to the forward end of the lever d by turning the rod d^{13} and worm d^{12} . It will also be seen that the platform-frame and parts carried thereby may be vertically moved from both ends by the movement of the levers c and d on their fulcrums. This is the ordinary and quickest way of adjusting the same, and I provide means for facilitating this movement, which will now be described.

On a platform or deck b^{10} , which covers the rear portion of the truck-frame b , and just forward of the driver's seat b^{11} , I mount three controlling-levers $f f' f^2$. The central member f of these levers works between the blades f^3 of a slotted or bifurcated latch-arch bracket f^4 and has its hub pivotally mounted in a bearing f^5 , located at the radial center of said arch-blades f^3 . The bracket f^4 is rigidly secured to the deck b^{10} . The hub of the lever f carries at its end bifurcated latch-arches f^6 and f^7 , between which the levers $f' f^2$, respectively, work. The levers $f f' f^2$ are provided with hand-operated spring-latch pawls $f^8 f^9 f^{10}$, which co-operate with their respective latch-arches to secure said levers wherever set. The outside levers $f' f^2$ are rigidly secured, respectively, on the ends of transverse shafts $f^{11} f^{12}$, mounted in suitable bearings f^{13} , secured on the deck b , with their centers in line with the pivotal center of the hub of the lever f .

The shaft f^{12} extends to the right of the

machine and has secured to its outer end an arm f^{14} , the free end of which is attached to the rear end of the lever c by means of a slot-and-pin connection f^{15} .

5 The shaft f^{11} extends to the left of the machine, and has secured to its outer end a short lever f^{16} .

f^{17} is a bell-crank lever pivoted at its fulcrum on a bracket f^{18} , projecting from and rigidly secured to the frame b . The lower arm of this bell-crank f^{17} is attached by means of a slot-and-pin connection f^{19} to the rear end of the lever d , while the upper arm of the same is connected by means of a link f^{20} with the free end of the lever or arm f^{16} .

In virtue of the levers and other raising and lowering connections above described the following actions are made possible: The operator, by drawing the free end of the lever f^{17} toward the rear of the machine, will carry the latch-arches f^6 and f^7 also to the rear, and hence, through the levers f' and f^2 and intermediate connections, will force the rear ends of the levers c and d downward, thereby simultaneously raising both ends of the platform-frame a . Again, by drawing the lever f^2 toward the rear the rear end of the lever c will be lowered and the right end of the platform-frame a will be raised without affecting the left end of the platform. On the other hand, if it is the lever f' that is drawn to the rear the rear end of the lever d will be lowered and the left end of the platform-frame a will be raised.

35 In all of the above actions it will be noted that the latch-arches f^3 f^4 serve as a base of resistance to retain all of the levers f' f^2 in position.

The above arrangement of levers and lifting connections, in virtue of which the platform and cutting devices of the harvester may be adjusted either simultaneously or independently from its opposite ends, is an extremely desirable construction. The purposes accomplished by means of these variable adjustments will be readily understood to all persons familiar with the handling of harvester-machines. In brief, it permits the platform and cutting devices to be set longitudinally parallel with the ground, or at an angle thereto, and then to be moved vertically without changing the angle or parallelism of said platform.

Returning now to the motor carried by the truck-frame and the series of independent driving connections therefrom to the traction-wheels and to the harvesting devices of the machine, attention is directed first to Figs. 1 and 2. As here shown, I employ a gas, gasoline, or oil engine, of any ordinary standard type suitable for the purpose, of which g is the cylinder; g' , the piston-rod; g^2 , the crank-shaft; g^3 , a pair of fly-wheels secured on the opposite ends of the crank-shaft g^2 ; and g^4 is the bed or frame, which bed is bolted to the top of the deck b^{10} , forward of the levers f' f^2 . The valve-gear and certain other parts

of the engine have been omitted from the drawings, but it will be understood, of course, that they may be of the ordinary construction. For use in connection with this gasoline-engine I have shown an ordinary cold-water tank g^5 and gasoline-tank g^6 , which are secured to the deck b^{10} , as shown in Figs. 1 and 2.

70 Before proceeding farther, it may be well to remark that all of the sprocket-chains illustrated in connection with the following drives or driving mechanisms have, for the sake of clearness, been indicated on the drawings simply by dotted lines.

The independent guides which extend one from each of the drive-wheels g^8 , respectively, to the traction-wheels and to the harvesting devices are in the following respects substantially alike, and similar parts will be marked with the same letters. Referring to these parts, k indicates a pair of short shafts which are located axially in line with the engine crank-shaft g^2 and extend one to the right 80 and the other to the left from said crank-shaft and are loosely mounted in rectangular bearing-frames k' , rigidly supported one from each side of the truck-frame b . These shafts k are adapted to be independently connected to their respective coöperating fly-wheels g^9 by means of friction-clutches. As shown, these friction-clutches comprise each a sliding head k^2 , secured to the shaft k by means of a groove and feather, (not shown,) 90 friction-shoes k^3 , engageable with the interior of the rim of the fly-wheel g^9 , and links k^4 , connecting said shoes k^3 with said sliding head k^2 . By moving the sliding head k^2 toward the fly-wheel g^9 the shoes k^3 will be 100 forced into frictional engagement with the rim of said fly-wheel and the shaft k will be caused to revolve. As is evident, the outward movement of said sliding head k^2 will 110 retract the shoes k^3 and cause the shaft k to remain at rest. The movements of these sliding heads k^2 are preferably controlled by means of shipper-levers k^5 , having the ordinary pin-and-groove connection therewith. As shown, these levers k^5 are pivoted to the 115 framework at k^6 and are held wherever set by means of latch-plates k^7 .

Returning to the shafts k , k^8 indicates a series of half-clutches which are fixed on each of said shafts by means of pins or otherwise. 120 k^9 indicates corresponding series of sprocket-wheels loosely mounted on said shafts k and provided with half-clutches coöperating with the half-clutches k^8 .

k^{10} indicates a pair of counter-shafts located 125 one in advance of and parallel to each of the shafts k . These shafts k^{10} are also loosely mounted in the rectangular bearing-frames k' and are provided with fixed half-clutches k^{11} , corresponding to the fixed half-clutches k^8 130 on the shafts k . k^{12} indicates corresponding series of sprocket-wheels loosely mounted on said shafts k^{10} and provided with half-clutches coöperating with the fixed half-clutches k^{11} .

By reference to Fig. 1 it will be noted that the series of sprocket-wheels k^{12} on the shafts k^{10} increase in size from the center of the machine outward.

5 The sprocket-wheels k^9 and k^{12} , which are located in line with each other longitudinally of the machine, are connected in pairs by means of sprocket-chains k^{13} . It will thus be seen that the inner pairs of sprocket-wheels k^9 k^{12} , when thrown into action, will drive the counter-shafts k^{10} at a higher rate of speed than would any of the corresponding pairs of wheels that are located farther out.

10 The means which I have shown for throwing any one of the pairs of sprocket-wheels k^9 k^{12} into action at will is as follows: The sprocket-wheels k^9 and k^{12} are provided on their hubs with annular collars k^{14} , which work between keeper-brackets k^{15} , carried by 15 shipper-bars k^{16} . These shipper-bars, it will be noted, are perforated and slide loosely on the shafts k and k^{10} , and the keeper-brackets k^{15} carried thereby also connect said sprocket-wheels k^9 and k^{12} in pairs. Hence, by moving the shipper-bars k^{16} laterally any pair of 20 sprocket-wheels k^9 k^{12} may be engaged with the coöperating pairs of fixed half-clutches k^8 k^{11} . The independent movement of these shipper-bars k^{16} is accomplished as follows: 25

30 k^{17} are rock-shafts in parallel arrangement longitudinally of the machine, mounted in the rectangular bearing-frames k' and in bearing-blocks k^{18} at the rear of the truck-frame b . These rock-shafts k^{17} correspond in number to the number of shipper-bars k^{16} and co-operate one with each of the same. The rods k^{17} or rock-shafts are provided with upwardly-extending pairs of parallel arms k^{19} , which are connected by means of slot-and-pin connections k^{20} with the opposite ends of the shipper-bars. At their rear ends the rock-shafts k^{17} are provided with inturned levers k^{21} , which are held in either of two positions by means of notched lock-plates k^{22} .

45 With the above construction it is obvious that the operator, from the seat b^{11} , may readily move any one of the levers k^{21} , and through the rock-shafts k^{17} , arms k^{19} , and shipper-bars k^{16} may render operative or inoperative at will any pair of sprocket-wheels k^9 k^{12} , and hence may vary at will the speeds of the shafts k^{10} with respect to each other or to the speed of the engine.

55 Of the two independent drives above described it may be well to observe at this point that the sprocket wheel and chain connections which are located at the right-hand side of the engine constitute part of the variable drive to the harvesting mechanism, 60 while like parts which are located at the left-hand side of the machine constitute part of the variable drive to the traction-wheels of the truck. From this point on the independent drives are essentially different in construction and will be described separately.

65 Referring to the drive to the cutting devices, it will be noted, by reference to Fig. 1,

that the inner end of the variably-driven counter-shaft k^{10} is provided with a rigid sprocket-wheel k^{23} .

70 k^{24} is a transverse counter-shaft mounted in bearings k^{25} , fixed to the rear right end of the platform-frame a and provided with a bevel-wheel k^{26} at its right end and at its left end with a sprocket-wheel k^{27} , located in line with the sprocket-wheel k^{23} .

75 k^{28} indicates a sprocket-chain passing over the wheels k^{23} and k^{27} .

80 It will be noted that the shaft k^{24} on the platform-frame a serves as a common shaft from which all parts of the harvesting mechanism—*i. e.*, the binder, (not shown,) the sickle, the canvases, and the reel (not shown)—are driven, and that this shaft k^{24} is driven directly from the right-hand member of the 85 counter-shafts k^{10} . The slack of this chain is automatically taken up by means of a sprocket-like chain-tightener k^{29} , mounted on one of the cross-beams of the truck-frame b .

90 k^{30} is a bevel-wheel carried on the rear end of the pitman crank-shaft a^5 and in engagement with the bevel-wheel k^{26} on the shaft k^{24} .

95 Complete driving connections between the fly-wheels g^3 of the engine and the harvesting mechanism have now been described, and since, as already clearly pointed out, the shaft k^{10} may be variably driven, it will of course necessarily follow that said harvesting mechanism may also be variably driven.

100 k^{31} indicates a sprocket-wheel on the rear end of the pitman-shaft a^5 , just inward of the bevel-wheel k^{30} . This sprocket-wheel k^{31} serves to impart motion to the binding mechanism. (Not shown.)

105 The binder or binding mechanism, it will of course be understood, will be carried by and supported from the platform-frame a in the ordinary manner. The binder being driven from the variable drive, as above described, it will of course follow that the binder and binding mechanism of the same will be driven at a speed proportioned to the speed of the cutting devices.

110 Returning now to the variable drive to the traction-wheels, it will be noted, by reference to Fig. 1, that the shaft k^{10} is near its inner end provided with a rigidly-secured sprocket-wheel k^{32} . k^{33} is a divided shaft mounted in suitable bearings in the truck-frame b and provided at its opposite ends with pinions k^{34} , 120 engaging with internal gear-teeth b^{12} , formed on the interior rims of the traction-wheels b' . The sections of the shaft k^{33} are connected by means of an ordinary compensating-gear k^{35} , having a main sprocket-wheel k^{36} , located in 125 line with the sprocket-wheel k^{32} . k^{37} indicates a sprocket-chain passing over the sprocket-wheels k^{32} k^{36} .

130 A complete variable drive between the engine and the traction-wheels has now been described.

Inasmuch as a gas-engine cannot be reversed I find it necessary, in the particular arrangement described, to provide a revers-

ing device by means of which the traction-wheels may be reversed and the machine backed up. As shown, this reversing device comprises the following mechanism: p indicates a sprocket-wheel loosely mounted on the inner end of the right-hand member of the shafts k just inward of the rectangular frame k' . This wheel p is provided with a half-clutch, which is adapted to be engaged by a sliding half-clutch p' , mounted for sliding movement on said shaft k by means of a groove and feather. (Not shown.) p^2 is a spur-gear loosely mounted on the inner end of the left-hand member of the counter-shafts k^{10} . This spur-gear p^2 is provided with a half-clutch, which is adapted to be engaged by a sliding half-clutch p^3 , mounted for sliding movement on said counter-shaft k^{10} by means of a groove and feather. (Not shown.) p^4 is a transverse counter-shaft mounted in bearings p^5 on the frame b and provided at its right end with a sprocket-wheel p^6 in line with the sprocket-wheel p and at its left end with a spur-wheel p^7 , engaging the spur-wheel p^2 . p^8 indicates a sprocket-chain passing over the sprocket-wheels p and p^6 . p^9 and p^{10} indicate shipper-levers pivoted, respectively, at p^{11} and p^{12} to the frame b and having the ordinary pin-and-groove connections, respectively, with the sliding half-clutches p' and p^3 . The forward ends of these shipper-levers p^9 and p^{10} are connected by a link p^{13} . The free end of the lever p^9 projects rearward to a point opposite the driver's seat, at which point it is secured to a hand-lever p^{14} . The operation of this reversing device is apparent. Before throwing the reversing device into action the variable-driving devices should be thrown out of action. Then by moving the rear end of the lever p^9 toward the right both of the half-clutches p' and p^3 will be simultaneously thrown into action with the half-clutches of the wheels p and p^2 , respectively, and the reverse motion of the traction-wheels thereby effected.

Attention is here recalled to the friction-clutch devices k^2 k^3 k^4 used in connection with the fly-wheels k^3 . In all of the above-described driving actions, either forward or reverse movement, these friction-clutches serve to gradually apply the driving power to the different parts of the machine, and thereby eliminate the possibility of breakage from sudden applications of the driving power. In the reversing action only the right-hand section-clutch is operative.

In the accompanying drawings no special means has been shown for controlling the tilting movement or dip of the platform a , but it will be understood, of course, that any means suitable for this purpose might be employed.

The truck-frame b is shown as trussed and braced by means of a vertical standard b^{13} , rising from said frame b , and stay-rods b^{14} ,

running from the top of said post b^{13} and connected to different parts of said frame b .

The variable drives or driving mechanisms whereby the harvesting mechanism may be driven at different rates of speed with respect to any given speed of advancing movement of the harvester is thought to be a novel and valuable improvement in harvesting machinery, and is of especial value when used in connection with harvesters of very large capacity, such as the motor-driven harvester here shown. It enables the binding mechanism, as well as the cutting and delivery devices, to be run at a very high rate of speed when very heavy grain is encountered, so that the grain may be handled and bound with such increased rapidity that the determined and desired rate of advancing movement of the machine need not be interfered with. Again, instead of increasing the speed of the harvesting devices on encountering heavy grain the advancing speed of the machine may be decreased, or at one and the same time the speed of the harvesting mechanism may be increased and the advancing movement of the machine decreased. Obviously this variable drive might be applied to mowers and similar machines as well as to grain-harvesters.

It will be understood, of course, that various alterations in the details of construction of my invention may be made without departing from the principles of the same. For instance, the variable drives instead of being entirely independent of each other throughout their entire extent, as shown, might have certain of their parts in common and only the variable parts arranged independent of each other. Again, as is obvious, the drive might be applied to one or more of the traction-wheels.

What I claim, and desire to secure by Letters Patent of the United States, is as follows:

1. In a harvester or similar machine, the combination with the traction wheel or wheels and harvesting mechanism, of a motor mounted on the machine-frame and independent variable drives extending from said motor, one to said traction-wheels, and the other to said harvesting mechanism, whereby the speeds of said traction-wheels and harvesting mechanism may be varied with respect to each other and to said motor, substantially as described.

2. In a harvester or similar machine, the combination with the traction wheel or wheels and the harvesting mechanism, of a motor mounted on the machine-frame, and independent variable drives extending from said motor, one to said traction-wheels and the other to the harvesting mechanism, each of said variable drives involving in the combination, a series of intermediate driving connections geared for different speeds, and means for rendering any one of said intermediate connections operative on said drives at will, substantially as described.

3. In a harvester or similar machine, the combination with the traction wheel or wheels and the harvesting mechanism, of a motor mounted on the machine-frame, and independent variable drives extending from said motor one to said traction-wheels and the other to said harvesting mechanism, each of said variable drives involving in the combination, a series of intermediate sprocket-wheel and chain connections geared for different speeds, and means for rendering any one of said connections operative on said drives at will, substantially as described.

4. In a harvester or similar machine, the combination with the traction wheel or wheels and the harvesting mechanism, of a motor mounted on the machine-frame, and the independent variable drives extending from said motor, one to said traction-wheels, and the other to said harvesting mechanism each of said variable drives involving in the combination the loosely-mounted parallel counter-shafts, the half-clutches carried by said counter-shaft, the loose sprocket-wheels on said counter-shafts provided with half-clutches co-operating with said fixed half-clutches, the chains connecting said sprocket-wheels in pairs, the laterally-movable shipper-bars with keepers engaging the hub of said sprocket-wheels, the rock-shafts and parallel arms connected to said shipper-bars, levers on said rock-shafts, and a clutch for connecting one

of said counter-shafts with a rotary part of the engine, substantially as described.

5. In a harvester or similar machine, the combination with the cutting device and support for the same, of raising and lowering connections applied to the opposite ends of said support, said connections involving in the combination, the bifurcated fixed latch-arch bracket, the primary latch-lever working between the blades thereof, the pair of movable bifurcated latch-arches carried by said primary lever, and the secondary latch-levers working independently, one between the blades of each of said movable arches and provided with connections to the opposite ends of said support, substantially as described.

6. In a harvester or similar machine, the combination with the traction-wheels and harvesting mechanism, of a motor mounted on the machine-frame, independent variable drives from said engine respectively to said traction-wheels and to said harvesting mechanism and a reversing device, involving a pair of clutches connected for simultaneous movement, substantially as described.

In testimony whereof I affix my signature in presence of two witnesses.

CHARLEY A. KULBERG.
